(57) **CLAIM**

The ornamental design for electronic computer, as shown and described.

DESCRIPTION

FIG. 1 is a reduced top, front and right side perspective view of an electronic computer showing our new design,
FIG. 2 is a reduced bottom, front and right side perspective view thereof,

FIG. 3 is a front elevational view thereof,

FIG. 4 is a rear elevational view thereof,

FIG. 5 is a left side elevational view thereof,

FIG. 6 is a right side elevational view thereof,

FIG. 7 is a top plan view thereof,

FIG. 8 is a bottom plan view thereof,

FIG. 9 is a front elevational view showing the article in a closed position thereof,

FIG. 10 is a right side elevational view showing the article in the closed position thereof; and,

FIG. 11 is a top plan view showing the article in the closed position thereof.

The broken lines are shown in the views for illustrative purposes only and form no part of the claimed design.
